CLAIM

I claim the ornamental design for a livestock tag, as shown and described.

DESCRIPTION

FIG. 1 is a top perspective view of a livestock tag;
 FIG. 2 is a bottom perspective view of the livestock tag of FIG. 1;
 FIG. 3 is a top view of the livestock tag of FIG. 1;
 FIG. 4 is a front elevation view of the livestock tag of FIG. 1;
 FIG. 5 is right side view of the livestock tag of FIG. 1;
 FIG. 6 is left side view of the livestock tag of FIG. 1;
 FIG. 7 is a rear elevation view of the livestock tag of FIG. 1;
 and,
 FIG. 8 is a bottom view of the livestock tag of FIG. 1.
